UNITED STATES PATENT OFFICE.

GEORGE LUX, OF QUAKERTOWN, PENNSYLVANIA.

SHUTTLE SPINDLE AND COP-TUBE HOLDER THEREFOR.

Application filed December 5, 1923. Serial No. 678,653.

To all whom it may concern:

Be it known that I, GEORGE LUX, citizen of the United States, residing at Quakertown, in the county of Bucks and State of Pennsylvania, have invented certain new and useful Improvements in Shuttle Spindles and Cop-Tube Holders Therefor, of which the following is a specification.

This invention relates to textile weaving apparatus, and has particular reference to an improved form of shuttle spindle and cop tube holder therefor.

The primary object of the invention is to provide a shuttle spindle and a cop tube holder having cooperative means for positively holding cop tubes upon such spindle.

Another object is to provide a device constructed to receive and effectively hold a cop tube, and to provide a special form of shuttle spindle for reception of said cop tube holder, the cop tube holder and spindle being provided with cooperative means for effectively retaining the cop tube holder upon said spindle.

Still another object of the invention is to provide a shuttle spindle and cop tube holder therefor, which embrace the desired qualities of simplicity and durability of construction, as well as efficiency in operation, in preventing slipping of the cop tube from the spindle.

Still another object of the invention is to provide for the effective mounting of cop tubes upon shuttle spindles with facility and ease and without requiring twisting or other distortion of the cop tube, such as would result in loosening the silk or cotton wound upon the tube as well as wasting of such silk or cotton, and whereby the cop tube will be preserved for re-use.

Other objects will appear as the nature of the invention is better understood, and the same consists in the novel form, combination, and arrangement of parts herein-after more fully described, shown in the accompanying drawing, and claimed.

In the drawings, wherein like reference characters indicate corresponding parts throughout the several views:

Figure 1 is a side elevational view showing a shuttle spindle and a cop tube holder therefor constructed in accordance with the present invention, the cop tube holder being locked to the spindle.

Figure 2 is a bottom plan view of the

device shown in Figure 1, with the cop tube illustrated in position by dotted lines.

Figure 3 is a view similar to Figure 1, of the shuttle spindle with the cop tube holder removed, and

Figure 4 is a transverse sectional view taken substantially upon the line 4-4 of Figure 1.

Referring more in detail to the drawings, 5 indicates the shuttle spindle, which is pointed at its outer end as at 6, and which is enlarged in the usual manner as at 7, to provide a head formed with a transverse opening 8 by means of which the spindle is pivotally mounted in the shuttle, the head 7 being flat as at 9, on its upper side, for cooperation with the usual spring, not shown, by means of which the spindle is only swung into proper position longitudinally within the shuttle. The construction thus far described is usual and well known in the art and forms no part of the present invention, except in combination with construction to be now described.

As shown clearly in Figure 3, the inner end portion of the spindle 5 is tapered as indicated at 10 so as to gradually increase in diameter toward the head 7, and projecting outwardly and laterally from the head 7 and overhanging the inner end of the tapered portion 10 of the spindle 5 is a rigid hook member 11, whose free end is directed toward the spindle as indicated at 12.

The cop tube holder consists of a tapered sleeve 13, that is tapered both externally and internally, whereby said sleeve may be fitted onto the tapered portion 10 of the spindle 5, snugly but rotatably, for a purpose which will presently become apparent. The outer end of the sleeve 13 is provided with a plurality of longitudinal slots as at 14 so as to divide the outer end of said sleeve into a plurality of jaws 15 that are resilient and normally contracted to permit the larger end of the usual cop tube indicated by dotted lines at 16, in Figure 2, to be fitted thereon. The jaws 15 are normally contracted so that when the sleeve 13 of the cop tube holder is forced toward the head 7 of the spindle 5 beyond a predetermined point, the jaws 15 will be slightly expanded, so as to tightly grip the interior of the larger end of the cop tube 16, whereby accidental slipping of said cop tube off of the holder sleeve 13 is prevented.

The present invention embodies the provision of means for causing this longitudinal movement of the sleeve 13 toward the head 7, for securing the cop tube upon said sleeve 13, and this means preferably constitutes means for also positively locking the sleeve 13 on the tapered portion 10 of the spindle. In the form of the invention shown, this means comprises an annular flange 17 that is rigid with the inner end of the sleeve 13, and that is provided with a cam face along which the inwardly directed free end portion of the hook member 11 is adapted to ride when the spindle 5 and sleeve 13 are relatively rotated for causing movement of the sleeve 13 toward the head 7 as mentioned above. In order to permit engagement of the sleeve 17 behind the hooked end 12 of the hook 11, said flange 17 is provided with a peripheral notch, as at 18, adapted to be aligned with the end 12 of the hook 11, when the cop tube holder is slipped onto the spindle. The notch 18 is slightly wider than the hook 11, so that the flange 12 may pass the free end of said hook, after which the relative rotation referred to above results in engagement of the hook behind the flange 17 for positively locking the cop tube holder upon the spindle, and for urging it toward the spindle head, so as to expand the jaws 15 into tight gripping engagement with the interior of the cop tube 16. By simply reversing this operation, the cop tube holder may be readily removed, whereupon the jaws 15 will automatically contract so that the cop tube may be removed therefrom and a new cop tube substituted upon which an additional supply of thread is wound.

It is thus apparent that the use of the present device requires no damage or distortion of cop tubes, and that the latter may accordingly be reused with a great savings resulting. It is the usual practice of twisting these cop tubes to maintain them upon the shuttle spindle somewhat ineffectively, and such twisting results in loosening the silk or cotton wound upon the cop tube with a resultant waste of such silk or cotton. The present invention eliminates waste of the cotton from this source.

Numerous advantages of a device constructed in accordance with the above will present themselves to those skilled in the art, and it is noted that minor changes may be made without departing from the spirit and scope of the invention as claimed.

What I claim as new is:

1. In a device of the character described, the combination with a shuttle spindle, of a cop tube holder comprising a sleeve positionable upon the spindle and formed to provide a plurality of jaws onto which a cop tube is adapted to be positioned, means to expand the jaws into tight engagement with the cop tube upon movement of the cop tube

holding sleeve onto the spindle beyond a predetermined point, and means to cause such movement of the cop tube sleeve onto the spindle beyond such predetermined point. 70

2. In a device of the character described, the combination with a shuttle spindle, of a cop tube holder comprising a sleeve positionable upon the spindle and formed to provide a plurality of jaws onto which a cop tube is adapted to be positioned, means to expand the jaws into tight engagement with the cop tube upon movement of the cop tube holding sleeve onto the spindle beyond a predetermined point, means to cause such movement of the cop tube sleeve onto the spindle beyond such predetermined point, and to simultaneously positively lock the cop tube holding sleeve on the spindle. 75 80

3. In combination with a shuttle spindle having a head at its inner end adapted for pivotal connection with a shuttle and formed with a tapered inner end portion that increases gradually in diameter toward the spindle head, a cop tube holder including a sleeve tapered internally and externally and adapted to fit the tapered portion of the spindle, said cop tube holding sleeve being provided with a plurality of jaw members expansible by the tapered portion of the spindle into gripping engagement with the interior of a cop tube, when said cop tube holding sleeve is moved onto the spindle toward its head beyond a predetermined point. 85 90 95

4. In combination with a shuttle spindle having a head at its inner end adapted for pivotal connection with a shuttle and formed with a tapered inner end portion that increases gradually in diameter toward the spindle head, a cop tube holder including a sleeve tapered internally and externally and adapted to fit the tapered portion of the spindle, said cop tube holding sleeve being provided with a plurality of jaw members expansible by the tapered portion of the spindle into gripping engagement with the interior of a cop tube, when said cop tube holding sleeve is moved onto the spindle toward its head beyond a predetermined point. 100 105

4. In combination with a shuttle spindle having a head at its inner end adapted for pivotal connection with a shuttle and formed with a tapered inner end portion that increases gradually in diameter toward the spindle head, a cop tube holder including a sleeve tapered internally and externally and adapted to fit the tapered portion of the spindle, said cop tube holding sleeve being provided with a plurality of jaw members expansible by the tapered portion of the spindle into gripping engagement with the interior of a cop tube when said cop tube holding sleeve is moved onto the spindle toward its head beyond a predetermined point, and means to simultaneously lock the cop tube holding sleeve upon the spindle and to cause its movement relative to the spindle toward the head beyond said predetermined point. 110 115

5. In combination with a shuttle spindle having a head at its inner end adapted for pivotal connection with a shuttle and formed with a tapered inner end portion that increases gradually in diameter toward the spindle head, a cop tube holder including a sleeve tapered internally and externally and adapted to fit the tapered portion of the spindle, said cop tube holding sleeve being provided with a plurality of 120 125 130

jaw members expandable by the tapered portion of the spindle into gripping engagement with the interior of a cop tube, when said cop tube holding sleeve is moved

of the cop tube holding sleeve is had for expanding its jaws upon relative rotation of the spindle and cop tube holder, said cop tube holding sleeve being longitudinally slotted to provide such jaws in normally contracted resilient form. 50

5 onto the spindle toward its head beyond a predetermined point, means to simultaneously lock the cop tube holding sleeve upon the spindle and to cause its movement relative to the spindle toward the head, beyond
